UNITED STATES PATENT OFFICE.

SAMUEL T. SKEEN, OF CENTRALIA, ILLINOIS, ASSIGNOR, BY DIRECT AND MESNE ASSIGNMENTS, TO THE S. & S. MANUFACTURING COMPANY, A PARTNERSHIP COMPOSED OF SAMUEL T. SKEEN AND CHARLES E. STEAD.

DRILL.

Application filed October 6, 1924. Serial No. 741,880.

This invention relates to a drill particularly adapted for use in drilling into coal deposits, one of the objects being to provide a very simple and inexpensive miner's drill 5 having a blade, or bit, which may be easily detached from the drill stem with which it is associated. The blade is preferably formed of a single piece of metal and is rigidly secured to an end portion of a long spiral 10 stem, and since the blade is a small and inexpensive article it may be economically made of a high grade material well adapted to withstand the service to which it is subjected.

15 An important advantage in connection with my drill is that the blades, being detachable, may be removed from the stems and replaced by other blades whenever necessary, thereby eliminating the necessity of 20 taking the drill stems from the mines to sharpen the cutting blades as is ordinarily done. Due to the fact that the wear is on the detachable blades and not on the drill stems, it is apparent that a single drill stem 25 may be used for a long period of time.

With the foregoing and other objects in view, the invention comprises the novel construction, combination and arrangement of parts hereinafter more specifically described 30 and illustrated in the accompanying drawings, wherein is shown the preferred embodiment of the invention. However, it is to be understood that the invention comprehends changes, variations and modifications 35 which come within the scope of the claim hereunto appended.

Fig. I is a view of the lower portion of a drill constructed in accordance with my invention.

40 Fig. II is a view looking in the direction indicated by the feathered arrow adjacent to Fig. I.

Fig. III is a fragmentary vertical section showing the manner in which the blade of my improved drill is attached to the stem thereof.

Fig. IV is a view showing the lower bifurcated end portion of the stem of my improved drill.

50 Fig. V is a perspective of the blade of my improved drill.

Fig. VI is a horizontal section on the line VI—VI of Fig. I.

In the drawing, A designates a drill stem

in the form of a spiral conveyor and having 55 a lower bifurcated end portion B, the oppositely disposed legs of said bifurcated end portion B being provided with registering openings C which are intended for a purpose to be hereinafter set forth.

The blade D of my improved drill is preferably formed of a single piece of material and is provided with a pair of cutting edges 1. Located at the upper edge of the blade D is a notch 2, and formed through said blade at a point approximately intermediate of the upper and lower edges thereof is an opening 3, said opening 3 being approximately the same diameter as the openings C formed through the legs of the bifurcated 70 lower end portion B of the drill stem. The blade D is provided with a flat intermediate portion D^a and a pair of outwardly bent wings D^b at the lower edges of which the cutting edges 1 are located.

To assemble the drill stem and the blade of my improved drill the flat intermediate portion D^a of the blade D is introduced between the legs of the bifurcated lower portion B of the drill stem, and said blade is 80 moved upwardly into the space between the legs of said bifurcated portion until the opening 3 in the blade D registers with the opening C in the legs of said bifurcated end portion B. A bolt 4 is then passed through 85 the registering openings C and 3 and a nut 5 is screwed on the threaded end of the bolt 4 and is caused to bear firmly against the outer face of the adjacent leg of the bifurcated end portion B. When the drill stem and blade 90 are assembled as described, the portion of the stem which is located at the top of the space between the legs of the bifurcated portion B and which is designated by the reference character 6 extends into the notch 2 at 95 the upper edge of the blade, the upwardly extending walls 2' of said notch 2 embracing said portions 6. This arrangement will eliminate any tendency for the blade D to pivot about the single fastening device, 100 namely, the bolt 4.

In connection with the invention disclosed herein there are two extremely important features, aside from the simplicity of the device, which should be noted. The first feature referred to is the very rigid and durable structure produced at the bifurcated end of the drill stem A. It is apparent that

the strain produced when the drill is being used is transferred from the blade D through the legs of the bifurcated end portion B of the stem to said stem. It is also plain that 5 a very rigid structure must be provided at the point mentioned, otherwise the legs of said bifurcated end portion would be snapped off. With the foregoing in mind, I 10 produce the stem A of my drill so that the spiral ribs A' forming a part of said stem extend downwardly and form integral parts 15 of the oppositely disposed legs of the bifurcated end portion B of the stem (Figs. I and VI). These spiral ribs function as strengthening flanges which strengthen the legs of 20 the bifurcated portion at the points where the greatest strain comes during the use of the drill and at the points where said legs would be most likely to snap in the absence 25 of strengthening means.

The second feature referred to is the arrangement of the spiral ribs A' of the stem A with relation to the cutting blade D of the drill. By referring to Fig. II of the 25 drawing it will be seen that the inclined edges D^c of the wings D^b of the blade follow the curvature, more or less, of the spiral ribs A' of the stem. In other words, spiral conveying means are provided which extend 30 continuously from the cutting edges of the blade to the opposite end of the drill stem A. This is important because it keeps the hole being drilled free from cuttings, as there are no breaks in the conveying means 35 where the propulsion of the cuttings is arrested.

It will be noted that the notch 2 is pro-

vided with inclined side walls (Fig. V). The reason for this arrangement is to insure contact between the side walls of the 40 notch and the portion 6 of the associated drill stem even through the blade D is used with drill stems having portions 6 of varying thicknesses. To permit the blade D to move vertically when drill stems having 45 portions 6 of varying thicknesses are used, I make the opening 3 in the blade D elongated as shown in Fig. V.

I claim:

In a boring tool, the combination with an 50 integrally formed single twist drill terminating in a pair of spaced, integral, oppositely disposed ears of approximately equal length, said ears being completely aligned with each other transversely of the major 55 axis of the drill and being arranged with portions of said single twist drill extended across faces thereof to add strength to said ears at points thereof which normally would be weak, of a single cutting blade adapted 60 to straddle the portion of the drill lying at the base of the spaced ears, and means for fastening the blade substantially midway of its longitudinal and transverse axis directly to the ears, said means being extended 65 through and supported at its opposite ends by said spaced ears, said cutting blade being so shaped that when secured to the drill the single twist is substantially uniform throughout the combined lengths of the drill and 70 the blade.

In testimony that I claim the foregoing I hereunto affix my signature.

SAMUEL T. SKEEN.
